UNITED STATES PATENT OFFICE.

THOMAS J. PILLIOD, OF SWANTON, OHIO.

VANITY CHEST.

Application filed April 28, 1926. Serial No. 105,239.

This invention relates to vanity chests and has for an object to provide an improved structure wherein cosmetic containers are arranged in separate compartments in a convenient manner and means are provided for supporting desirable articles other than cosmetic containers.

Another object of my invention is to provide a vanity case in which cosmetic containers are arranged in separate compartments adapted to conform to the contour of the container.

A still further object of my invention is to provide a vanity case provided with a compartment adapted to receive a candy box.

And another object of my invention is to provide a mirror positioned in the cover having a frame of a sufficient thickness that when the cover is closed the frame will rest against the lid of a candy box and serve to keep the candy box from rattling about in the vanity chest.

My vanity chest is also provided with a resilient lining adapted to cushion the candy box upon the bottom and also to cushion the tops of the cosmetic containers and my vanity chest is also provided with a resilient lining, the bottom of the box cushioning the bottom of the candy box and the lid when closed cushioning the tops of the cosmetic containers and preventing them from being disarranged or rattling about in their respective compartments.

Referring to the drawings:

Fig. 1 is a top plan view of my vanity chest.

Fig. 2 shows a front elevation of my vanity chest.

Fig. 3 is a sectional elevation of my vanity chest on the line 3—3 of Fig. 1.

Fig. 4 is a sectional elevation on the line 4—4 of Fig. 1.

Fig. 5 is a sectional elevation on the line 5—5 of Fig. 6.

Fig. 6 is a front elevation with the lid of the vanity chest standing open.

Referring more particularly to the drawings 1 represents the body portion of the chest with a lid 2 and a bottom 3.

The lid or cover is provided with a resilient material 4 as are also the sides and bottom of the chest. Centrally disposed on the inside of the cover is positioned a mirror 5 having a raised frame 6 adapted when the lid is closed to press against the cover 7 of

a container 8. A lock mechanism is shown at 9 and 10. Hinges are denoted by 11 and a cloth or other suitable material is provided and adapted to serve as a cover check 12 to hold the cover in a predetermined relation to the chest when the cover is opened. A comb is denoted by 13 and cosmetic containers by 14 and 15, each seated in a compartment having a contour adapted to provide a snug fit, respectively numbered 16, 17, 18 and 19.

The compartments 17 and 19 are formed in a block 20 and the compartments 16 and 18 are formed in a block 21. These blocks are preferably made of wood and securely fastened in the vanity chest.

A name plate is denoted by 22 and ornamental straps or plates are denoted by 23.

It will be noted that the container 8 as shown in Fig. 5 is supported by the bottom resilient cushion 4 when the chest is open and that when the chest is closed the resilient cushion 4 is depressed. It will also be seen that the resilient lining 4 of the cover is depressed by the articles 14 and 15 as shown in Fig. 3. The purpose of this resilient element being as explained above is to keep the container and articles from rattling when the chest is closed.

It will be understood that I do not limit my invention to the precise structure shown and described as it is apparent to anyone skilled in the art that I may make such changes and alterations as fairly come within the scope of the appended claims.

Having described my invention, what I claim as new and desire to secure by Letters Patent is:

1. A vanity chest of the character described, comprising a body portion; a cover hinged to said body portion; a mirror positioned in said cover; a frame for said mirror adapted to rest against and firmly hold a container, placed in said body portion, when the cover is closed.

2. A vanity chest of the character described, comprising a body portion; a cover hinged to said body portion; a mirror positioned in said cover; a frame for said mirror; and a resilient element applied to the bottom of said body portion; said frame and said element co-acting to firmly hold a container, placed in said body portion, when the cover is closed.

3. A vanity chest of the character described, comprising a body portion; means

for dividing said body portion into shallow compartments and a deep compartment; a cover hinged to said body portion; a mirror positioned in said cover; a frame for said mirror; and a resilient element applied to said cover; said frame and said element being respectively adapted to rest against and firmly hold a container placed in said deep compartment and articles placed in said shallow compartments. when the cover is closed.

4. A vanity chest of the character described, comprising a body portion; means for dividing said body portion into shallow compartments and a deep compartment; a

cover hinged to said body portion; a mirror positioned in said cover; a frame for said mirror; a resilient element applied to said cover; and a second resilient element applied to the bottom of said deep compartment; 20 said frame and said second element adapted to co-act to firmly hold a container placed in said deep compartment and said first resilient element adapted to firmly hold articles in said shallow compartments, when 25 the cover is closed.

In testimony that I claim the foregoing as my own, I affix my signature.

THOMAS J. PILLIOD.
